United States Patent

Des. 236,613

Patented Sept. 2, 1975

236,613

STORE BUILDING FAÇADE

Joseph Binder, Oceanside, N.Y., and Carl Palestini, Union City, N.J., assignors to The Bohack Corporation, Brooklyn, N.Y.

Filed May 29, 1973, Ser. No. 364,352

(Filed under Rule 47(a) and 35 U.S.C. 116)

Term of patent 14 years

Int. Cl. D25—03

U.S. Cl. D13—1 B

FIG. 1

FIG. 2

FIG. 4

FIG. 1 is a perspective view of the store building facade of our invention, illustrating the front and one side thereof;

FIG. 2 is a front elevational view of the store building facade of our invention;

FIG. 3 is a top plan view of the store building facade of our invention;

FIG. 4 is a side elevational view of the store building facade of our invention, showing, in particular, the entrance; and

FIG. 5 is a partial side elevational view of the store building facade of our invention, opposite to that illustrated in FIG. 4.

We claim:

The ornamental design for a store building facade, as shown.
